INTERNAL COMBUSTION ENGINE

Romeo M. Nardone, East Orange, N. J., assignor
to Bendix Aviation Corporation, South Bend,
Ind., a corporation of Delaware

Application February 15, 1939, Serial No. 256,575

1 Claim. (Cl. 123—179)

This invention relates to internal combustion engines, and particularly to the starting thereof.

It is common practice to employ, for starting an internal combustion engine, a separate unit ("starter") embodying a rotatable part normally disengaged from, but shiftable into engagement with, one end of the engine crank-shaft, or some part rotatable therewith. Thus, in aircraft engines, for example, there is provided a cylindrical (straight or tapered) flanged support, known as a "mounting flange" to receive such a starting unit, and within the cylindrical support are two correspondingly cut clutch elements, one of which is an integral part of the engine proper and rotates at all times with the engine crank-shaft, while the other is an integral part of the starting unit, and is normally spaced a fraction of an inch to the rear of the engine's clutch element. Upon energization of the starting unit the rotating starter clutch element moves forward and drivably engages the engine's clutch element, to impart initial rotary movement to the engine crank-shaft. Concurrently fuel and igniting sparks are supplied to the combustion chambers of the engine, in proper sequence; "starting" thereby results, whereupon the engine's clutch element—it is commonly called a "jaw"—overruns the starter jaw and the latter returns to its normal position of disengagement with respect to the rotating parts of the engine.

Prior to completion of the starting action the engine's clutch element may repeatedly overrun the starter jaw, as immediately after passing a high compression point or under an isolated firing impulse before the engine starts under its own power. These actions usually accelerate the engine much faster than the starter can follow; and before the resumption of the drive by the starter a "back-fire," or premature explosion in one of the cylinders, may occur, causing a "rocking back" of the engine jaw member with exceptional violence against the starter jaw.

Heretofore various means have been provided to save the starter unit from damage due to the actions above described; but practically all such means involve changes in the structure of the starter unit and also, in most instances, alter the mode of operation and the efficiency thereof in normal cranking—that is, on the more frequent occasions when there is no "back-firing" of the engine, and hence no need for the extra complications of the starter construction.

The present invention reflects a different concept, namely, that of meeting the "back-fire"

hazard by altering the engine proper, rather than the starter unit; and it is accordingly an object of the invention to provide a method of absorbing the effects of an engine "back-fire" without any change whatever in the structure or functioning of the normal engine starting mechanism.

Another object of the invention is to provide "back-fire" absorbing means operatively associated with the engine, but operatively dissociated from the normal engine starting parts.

Another object is to provide "back-fire" absorbing means adapted to fit within the usual cylindrical support to which the engine starter unit is attached, whereby the extent of alteration of the engine assembly is reduced to a minimum.

These and other objects of the invention will become apparent from inspection of the following specification when read with reference to the accompanying drawing wherein is illustrated the preferred embodiment of the invention. It is to be expressly understood, however, that the drawing is for the purpose of illustration only, and is not designed as a definition of the limits of the invention, reference being had to the appended claim for this purpose.

In the drawing reference character 5 designates a rotatable part of an aircraft engine of the type having a supercharger casing 6 providing bearing surfaces 7 and 8 to rotatably support the crank-shaft driven shaft 5, and also having a thickened section 9 presenting a plane annular surface concentric with shaft 5 and adapted to receive the tapered cylindrical support 11 which holds the starter unit 12 in position, the starter unit and the cylindrical support having registering flanges, as indicated at 13 and 14, to receive the supporting bolts 16.

The starter jaw 17 is disposed at the forward end of the unit 12, within the cylindrical support 11, and opposite the engine jaw 18 which, as shown, is integral with a socketed member or sleeve 19 which is positively connected to shaft 5 by suitable means 21. The pins 21 also serve to retain spacer 22 and member 23 in place, the former being interposed between combined thrust and radial bearings 24, and the member 23 being the outer race of a uni-directional roller clutch whose inner race 26 extends back over bearings 24 and receives a friction disc assembly 25 adapted to absorb the energy of a reverse rotational impulse imparted to shaft 5 by reason of a "back-fire" of the engine during the cranking operation. As shown the friction

discs include one group having grooves or splines for engagement with corresponding splines 27 cut on one section of the member 26, and each disc of this group alternates with a disc of the second group, the second group being those discs which are externally splined for engagement with corresponding splines 29 cut internally of the forward portion 31 of the supporting cylinder 11. The discs are held in frictional engagement between two pressure plates 33 and 34 by springs 36 and an annular member 37 which is adjustably secured to the threaded outer end 39 of member 26 and holds springs 36 in compression to the desired degree; the desired degree being preferably such as to dissipate the entire force of the reverse rotational impulse before the parts can rotate more than a fraction of a single revolution. Pressure plate 33 rests against a shoulder 41 on member 26, and serves as an abutment for the friction disc assembly.

During normal cranking the rollers 44 of the uni-directional clutch will roll freely in their cage 45, without transmitting any rotational effort to the inner race 26; but if and when a "back-fire" occurs these rollers will wedge be-

10 tween the two races and transmit the reverse rotational impulse to the friction disc assembly, where it will be dissipated without damage to or interference with the resumption of normal 15 cranking by the starter unit 12, whose jaw 17 remains meanwhile in engagement with engine jaw 18 and thereby facilitates such resumption of the cranking operation as soon as the effect of the "back-fire" has been absorbed in the disc assembly 25.

10 15 20 25 What I claim is:

The combination with an engine shaft, of a starter engageable therewith to turn said shaft in one direction, means including a plurality of rollers surrounding said shaft for facilitating initial rotation thereof by said starter, and constantly engaged friction means including a plurality of friction elements all of which remain stationary during normal starting of the engine, but some of which are rotatable with said rollers in a direction opposite to that in which said starter normally rotates, said friction means coacting with said rollers to resist such opposite rotation.

ROMEON M. NARDONE.
